US0D1099940S

(12) **United States Design Patent** (10) **Patent No.:** **US D1,099,940 S**
Amole et al. (45) **Date of Patent:** **** Oct. 28, 2025**

(54) **DISPLAY SCREEN OR PORTION THEREOF WITH GRAPHICAL USER INTERFACE**

(71) Applicant: **Apple Inc.**, Cupertino, CA (US)

(72) Inventors: **Oluwaseyi A. Amole**, San Jose, CA (US); **Lyam Joseph Bewry**, San Francisco, CA (US); **Andrew Patrick Clymer**, San Jose, CA (US); **Alan C. Dye**, San Francisco, CA (US); **Thalia Jimena Echevarria Fiol**, Cupertino, CA (US); **Bobby Cole Martin, Jr.**, Palo Alto, CA (US); **Marcel van Os**, Santa Cruz, CA (US); **Marcos Weskamp**, Palo Alto, CA (US); **Eric Lance Wilson**, San Jose, CA (US)

(73) Assignee: **Apple Inc.**, Cupertino, CA (US)

(**) Term: **15 Years**

(21) Appl. No.: **29/946,525**

(22) Filed: **Jun. 9, 2024**

(51) LOC (15) Cl. **14-04**

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
